Primary Examiner — Llorellys Martinez-Rivera(74) *Attorney, Agent, or Firm* — Dentons US LLP(57) **CLAIM**

The ornamental design for an earring, as shown and described.

DESCRIPTION

FIG. 1 is a perspective view of a first embodiment of an earring;

FIG. 2 is another second perspective view thereof;

FIG. 3 is another perspective view thereof;

FIG. 4 is a front view thereof; and

FIG. 5 is another perspective view thereof.

FIG. 6 is a perspective view of a second embodiment of the earring;

FIG. 7 is another perspective view thereof;

FIG. 8 is another perspective view thereof; and,

FIG. 9 is another perspective view thereof.

The broken lines in the drawings represent portions of the earring that form no part of the claimed design.

1 Claim, 9 Drawing Sheets(56)
